UNITED STATES PATENT OFFICE.

LEAH G. MILKES, OF MINNEAPOLIS, MINNESOTA.

DESIGN FOR A SLEEPING-ROBE.

47,494.

Specification for Design.

Patented June 22, 1915.

Application filed March 5, 1915. Serial No. 12,427. Term of patent 7 years.

To all whom it may concern:

Be it known that I, LEAH G. MILKES, a citizen of the United States, residing at Minneapolis, in the county of Hennepin and State of Minnesota, have invented a new, original, and ornamental Design for Sleeping-Robes, of which the following is a specification, reference being had to the accompanying drawings, forming part thereof.

Figure 1 is a plan view of the sleeping robe showing the same as it appears when closed up; and Fig. 2 is a plan view showing the robe as it appears when partly opened up.

I claim:

The ornamental design for a sleeping robe, as shown.

LEAH G. MILKES.
